ELECTRICAL BALLAST

Wesley W. Brooks, Fort Wayne, Ind., assignor to
 General Electric Company, a corporation of
 New York

Application September 25, 1947, Serial No. 776,082

5 Claims. (Cl. 323—44)

1

This invention relates to electrical ballasts and more particularly to improvements in ballasts for electric discharge devices.

An electric discharge device, as the term is here used, comprises essentially a pair (or more) of electrodes in an envelope containing an ionizable atmosphere. The discharge between the electrodes produces, among other well-known effects, radiation which may be visible or invisible. By making the envelope of glass, the device is widely used a lamp. By coating the glass, with a suitable phosphor invisible radiation is converted to light as in the well-known fluorescent lamp. Electrically, all such devices have the unstable characteristics of an arc and hence it is necessary to ballast them with a suitable series impedance or impedance network.

A well-known form of ballast is a high reactance transformer with a capacitor serially connected in its secondary circuit so as to make that circuit operate with leading current. By high reactance transformer is meant a transformer which is specially constructed to have a higher than ordinary leakage reactance. The voltage ratio of the transformer is so chosen as to transform any convenient supply voltage to the proper value for operating or starting the lamp. Some lamps, of either the hot or cold cathode type, have a separate starter which, among other things, initiates a transient boosting voltage for starting the lamp so that the transformer open circuit output voltage need not be enough to start the lamp. Other so-called instant start lamps, of either the hot or cold cathode type, have a ballast transformer whose steady state open circuit output voltage is sufficient to start the lamp.

One reason for operating the lamp circuit with leading current is that it is more stable than a corresponding lagging current circuit. An explanation of this is that the non-sinusoidal lamp current makes the lamp itself appear to have a lagging power-factor so that for the same circuit applied voltage and lamp voltage a net capacitive ballast has a higher impedance or higher ballasting voltage than a corresponding inductive ballast. Hence, the same variation in applied voltage and lamp characteristics will not produce as great a change in lamp current with a net capacitive (leading) ballast as with an inductive (lagging) ballast. Such a circuit can thus be used to operate both hot and cold cathode lamps of the same size at practically the same current. The term "net capacitive" is used because such a ballast is not simply a capacitor but includes also inductive reactance, which in the case of a

2

high reactance transformer is the reactance of the transformer. This inductive reactance controls the wave shape of the lamp current and it also provides the inductive kick which is initiated by the starter in the starting of certain lamps.

An objection to leading current operated ballasts is their poor power factor. Heretofore this has been overcome by combining a lagging current lamp circuit with the leading current lamp circuit as in a conventional unitary two lamp ballast.

In accordance with this invention the lagging current lamp circuit with its poorer regulating properties is eliminated, while at the same time achieving high power factor operation with one or more low leading power factor lamp circuits. This is accomplished by so constructing the high reactance transformer that it has an abnormally high exciting current which effectively neutralizes the wattless component of the leading load current. There are many specifically different ways of obtaining the high exciting current but they all employ the principle of increasing the reluctance of the part of the transformer core which is traversed by its magnetizing or exciting flux.

An object of the invention is to provide a new and improved electric ballast.

Another object of the invention is to provide a high power factor ballast for operating one or more electric discharge device circuits with low power factor leading current.

A further object of the invention is to provide a high exciting current two lead circuit high reactance transformer ballast for discharge lamps.

The invention will be better understood from the following description taken in connection with the accompanying drawing and its scope will be pointed out in the appended claims.

In the drawing Fig. 1 is a diagrammatic representation of a circuit embodying one form of the invention, Fig. 2 is a sectional view of one form of transformer used in this invention, Fig. 3 is vector diagram for explaining the operation of the invention, Figs. 4, 5, and 6 illustrate modified core structures suitable for use in this invention, and Fig. 7 illustrates a modified structural relation of the circuit elements.

Referring now to the drawing and more particularly to Fig. 1 the dashed line 1 indicates diagrammatically the enclosing casing of the ballast. This is a two lamp ballast which operates a pair of discharge lamps 2 and 3. The ballast comprises a high reactance transformer 4 and a pair of capacitors 5 and 6 which are connected respectively in series with the lamps 2 and 3. The

transformer comprises a magnetic core 1 on which are mounted windings 8, 9 and 10. Magnetic shunts 11 and 12 are provided on the core for increasing the flux leakage between the windings. Input terminals 13 are connected across the winding 8 which serves as the primary winding of the transformer. Windings 9 and 10 are auto-transformer connected with the primary winding 8. Thus the lamp 2 is connected across the windings 8 and 9 in series by way of a return conductor 14 and the capacitor 5 is serially connected in this circuit. Likewise, lamp 3 is connected across the supply circuit 13, which is the same as across the primary winding 8, through the winding 10, the capacitor 6 and the return conductor 14.

The reactance of the capacitors 5 and 6 is substantially higher, and in many cases roughly double, the leakage reactance of the transformer so that the secondary or lamp circuits of the transformer operate with leading current. In order substantially to neutralize this leading current the core 1 is provided with a high reluctance section in the form of an air gap 15 which is located on the part of the core which is surrounded by the primary winding 8. This high reluctance air gap causes the primary winding to draw a relatively high low power factor lagging exciting current.

Fig. 2 shows a shell type magnetic core construction in which gaps 16 are in series with the magnetic shunts 11 and 12 for giving them a relatively high reluctance so that they will not short circuit the exciting flux produced by the primary winding 8 and so that the open circuit output voltage of the transformer will be substantially proportional to its turn ratio. The core consists of three separate pieces per lamination layer one piece being a straight central leg member 17 and the other two pieces being duplicate four-legged yoke members 18. Instead of having a single gap 15 as in Fig. 1 the center part of the center leg 17 is provided with a series of gaps 15 whose ends are bridged by magnetic material at 19. These bridged gaps are easily made by punching slots in the lamination pieces.

The operation of the invention can best be explained by reference to Fig. 3 in which the vector E_p represents the voltage of the primary winding 8. The vectors I_{L1} and I_{L2} are the operating currents of the two lamps 2 and 3 whose sum is the vector I_L which is the total load current. In this diagram it should be understood that the current vectors are referred to the primary side of the transformer. It should also be understood that because of the non-sinusoidal currents taken by the lamps the diagram is not rigorously accurate although it is sufficiently accurate to illustrate the principle of operation of the invention. It will be seen that the load current I_L leads the supply voltage E_p by the angle θ . This leading power factor angle is the result of the voltage E_c of the capacitors 5 and 6. The leading load current in flowing through the series windings 9 and 10 causes both a change in magnitude and displacement in phase of the series winding voltage relative to the primary winding voltage so that the series winding voltage is represented by the vector E_s . The lamp operating voltage is the vector E_{Lamp} .

It will be observed that the lamp voltage and lamp current are slightly out of phase with the current lagging the voltage. This is not so much the result of any inherent reactance in the lamp itself as it is the result of the current

wave shape which causes a wattmeter to indicate that the lamp consumes less watts than it does volt-amperes.

The abnormally high exciting current of the transformer which is produced by the gap or gaps 15 is represented by the vector I_E which is shown lagging the primary voltage E_p by substantially 90 degrees. The size of the gap or gaps 15 is so chosen that the vector sum I_R of I_E and I_L is substantially in phase with the supply voltage E_p . As shown in the diagram the effect of I_E is to reduce the magnitude of the load current from I_L to I_R and also to reduce the input power factor of the ballast from the angle θ to the angle ϕ .

The modification shown in Fig. 4 employs a so-called forced core in which a straight leg portion 20 has its ends forced into suitable notches in a generally rectangular laminated yoke member 21 which is provided with the magnetic shunt members 11 and 12. In this modification the yoke member at 22 is restricted in cross section so as to provide the high reluctance section for increasing the magnetizing current.

The modification shown in Fig. 5 (which now constitutes the subject matter of my divisional application Serial No. 124,877, filed November 1, 1949, and assigned to the same assignee) differs from that shown in Fig. 2 in that instead of having bridged gaps 15-19 at the center of the leg portion of the core they are shown as bridged gaps 23 at the ends of the leg portion of the core. These bridged gaps therefore serve the double purpose of increasing the exciting current and limiting the transformer secondary flux due to the leading current in the series windings 9 and 10. This leading current tends to make the leakage flux of the windings 9 and 10 more or less in phase with the exciting flux produced by the winding 8 and without the gaps 23 the portions of the core traversed by the leakage flux of the windings 9 and 10 might saturate throughout the main body thereof and this would produce undesirable harmonics. This latter feature forms the subject matter of an application Serial No. 731,559, filed February 28, 1947, in the name of Harold W. Lord and assigned to the present assignee.

In the modification shown in Fig. 6 there is a core type core whereas Figs. 2, 4 and 5 have illustrated shell type cores. Each lamination layer of this core is made up of two punchings 24 and 25 with the ends of the outer legs of the members 24 shorter than the outer legs of the members 25. The two members are reversed in alternate layers so as to provide a lapped joint in the outer legs of the core. If desired a bridge gap can be formed in the outer legs by making the outer legs of the center lamination pieces substantially equal in length and so that their combined length is less than the total length of the outer legs. This will produce gaps indicated by the dotted lines 26 in the same way that the gaps 16 are provided in the magnetic shunts 11 and 12 and in the same way that the gap 15 is provided in the center leg of the core.

In Fig. 1, the capacitors 5 and 6 are connected respectively to what may be called the lamp ends of the secondary windings 9 and 10. In some cases, a more economical arrangement is to connect them as shown in Fig. 7 to the opposite or inner ends of the secondary windings 9 and 10. This is because the capacitors 5 and 6 can then be the two sections of a conventional double capacitor which is mounted in a single container

27. Such a double capacitor in a single case and with a midtap is ordinarily less expensive for the same amount of capacitor volt amperes than are two separate capacitors of the same total rating. It is also unnecessary to have three output leads extending from the ballast casing 1, and the conductor 14 may be a separate conductor which is not a part of the ballast and which is merely wired in place when the ballast is connected between its supply circuit and the lamps.

The flux density in the main body of all parts of the core is substantially uniform in all of the modifications. The bridged portions of certain of the gaps, which in effect are restricted sections somewhat analogous to the restricted sections 22 in Fig. 4 will, of course, operate at higher flux density than the rest of the core and may even saturate. However, in none of the modifications does the flux density of the main part of the core associated with the series windings 9 and 10 carry materially different flux density from the main part of the core carrying the primary winding 8.

Due to the low power factor leading current operation of the lamp circuits the operation of the invention does not depend in any way upon resonance in the lamp circuits.

It will of course be obvious that the invention does not depend upon the use of more than one lamp and series winding and that therefore either of the two lamp circuits may be omitted if desired and the device operated as a single lamp ballast. However, the two lamp construction is more economical than two single lamp constructions and it results in a balanced and efficient unit.

While there have been shown and described particular embodiments of the invention it will be obvious to those skilled in the art that changes and modifications can be made without departing from the invention and therefore it is aimed in the appended claims to cover all such changes and modifications as fall within the true spirit and scope of the invention.

What I claim as new and desire to secure by Letters Patent of the United States is:

1. An electric ballast comprising, in combination, a transformer having input and output circuits each including a coil on a unitary magnetic core, said core having a high reluctance magnetic shunt section between said coils for increasing the series reactance of said transformer and having a high reluctance series section for decreasing the exciting reactance of said transformer, the reluctance of said shunt section being higher than the reluctance of said series section, and a series capacitor in said output circuit, the reactance of said capacitor being of the order of at least twice the series reactance of said transformer, the exciting reactance of said transformer being such as substantially to neutralize in said input circuit the effect of the net capacitive reactance of said output circuit.

2. An electric ballast comprising, in combination, a transformer having input and output cir-

cuits each including a coil on a unitary magnetic core, said core having a high reluctance magnetic shunt section between said coils for increasing the series reactance of said transformer having a high reluctance series section for decreasing the exciting reactance of said transformer, the reluctance of said shunt section being higher than the reluctance of said series section, and a series capacitor in said output circuit, the reactance of said capacitor exceeding the series reactance of said transformer by approximately the exciting reactance of said transformer when referred to the output side of said transformer.

15. 3. In combination, an autotransformer having a magnetic core, spaced shunt and series windings on said core, high reluctance magnetic shunts between said windings for giving such series winding a relatively high leakage reactance, at least one high reluctance section in the portion of said core traversed by the flux of said shunt winding for giving said transformer a high exciting current, the reluctance of said shunts being higher than that of said high reluctance section, and a capacitor connected in series circuit relation with said series winding, said capacitor having a higher reactance than the leakage reactance of said series winding.

4. In combination, a balanced single phase 30 shell type magnetic core having a center leg section and divided yoke sections, a primary winding on the middle of said leg section, extended autotransformer windings on the opposite ends of said leg section, high reluctance magnetic 35 shunts separating said windings, and separate capacitors connected respectively in series with secondary windings which comprise respectively said primary winding in series with a different extended autotransformer winding, the capacitive reactance of said capacitors being substantially greater than the leakage reactance of said extended windings, the middle of said leg section having a high reluctance section for causing said primary winding to have an abnormally exciting current.

5. The combination as defined in claim 4 in which said capacitors are in a common container and have a common terminal.
